FIG. 4

INVENTOR:

Jacob Buehli,

By Henry Orth Jr. Atty.

UNITED STATES PATENT OFFICE

JACOB BUCHLI, OF WINTERTHUR, SWITZERLAND

LOCOMOTIVE

Application filed September 19, 1927, Serial No. 220,510, and in Germany October 27, 1926.

The subject matter of the present invention is a locomotive comprising two bogies connected with each other by means of combined draw and buffer-gear and a main frame 5 on which the driving motors (oil engines, benzine engines or electric motors) are rigidly fixed. The main frame carries the body in which the driver's cabs are arranged.

The bogies are provided with at least two driving axles coupled by means of parallel rods and with carrying axles, if required, and support the transmission gearings mounted in the frame of the bogies and consisting of at least one pair of spur gear wheels 15 and one pair of bevel gear wheels. Further change speed gears are provided which may be mounted on the main frame or on the frames of the bogies. To ensure proper driving conditions also when the locomotive negotiates curves between the parts mounted on the frames of the bogies and the parts mounted on the main frame Cardan shafts with universally movable couplings are interposed.

25 Two constructional examples of the subject matter of the present invention are diagrammatically illustrated on the accompanying drawings, in which

Fig. 1 shows in elevation a first constructional example of the locomotive,

Fig. 2 shows in a plan view the combined draw and buffer-gear,

Fig. 3 shows in an axial section a detail of Fig. 2, and Fig. 4 is an elevation view of a second constructional example.

Referring to Fig. 1, the bogies I and II are each provided with two driving axles 1 coupled with each other by means of parallel rods 2, and a carrying axle 3. On these axles 40 the bogie frames 4 and 4' respectively are supported through the intermediary of springs. In the bogie frames the pair of spur gear wheels 5, 6 is mounted; the crank shaft 7 on which the wheel 5 is fixed is connected by means of connecting rods 8 to the coupling rods 2.

On the shaft 9 is mounted a bevel gear wheel 10 or 10' respectively cooperating with a further bevel gear wheel 11 or 11' respectively which is also mounted in the frame

4 or 4' respectively. The frames 4, 4' of the two bogies are connected to each other by the draw and buffer-gear illustrated in detail in Figs. 2 and 3 and consisting of a rigid coupling member 12 and a diagonally arranged coupling member 12' provided with a coil spring 19 adapted to permit a relative displacement of the bogies when the vehicle negotiates curves and to return said bogies into their middle position on a straight portion of the track. The arrangement is such that the spring 19 is operative when the diagonally disposed rods approach each other or move away from each other. A more detailed description of this draw and buffer-gear is deemed unnecessary as it does not form part of the present invention.

The main frame 13 rests by means of pivot pins and sockets 14, 14' on the frames 4 and 4' of the bogies and is secured in a known manner by lateral supports against tilting. The main frame is covered by the body 15 in which the driver's cabs are provided and the auxiliary machines are housed.

On the main frame 13 the oil motors 16, 16' are mounted and rigidly connected to the latter, likewise the change speed gears 17, 17'.

The connection between the motors 16, 16' placed on the main frame 13 or between the change speed gears 17, 17' respectively and the transmission gearings 5, 6, 10, 11 or 5, 6, 10', 11' is effected by means of Cardan shafts 18, 18'. The latter transmit the turning moment of the motors to the pairs of bevel wheels 11, 10 and 11', 10' respectively and thereby to the crank shaft 7 and the driving axles connected thereto.

The constructional example illustrated in Fig. 4 differs from the example described above inasmuch as the change speed gears 17 and 17' are supported by the frames 4 and 4' of the bogies instead of by the main frame 13. The Cardan shafts 18 and 18' are in this case inserted between the motors 16, 16' and the change speed gears 17, 17'.

I claim:

1. A locomotive, comprising in combination, a main frame, two bogies having frames supporting said main frame by means of

5 pivots, two driving engines mounted on said main frame, driving wheels on said bogies, a transmission gearing and a lay shaft mounted on the frame of each bogie, a driving gear including coupling rods and connecting rods interposed between each transmission gearing and the driving wheels of a bogie, change speed gears, and Cardan shafts interposed between that part of the 10 driving means arranged on the main frame and that arranged on the frames of the bogies.

15 2. A locomotive comprising in combination, a main frame, two bogies having frames supporting said main frame by means of pivots, two oil engines mounted on said main frame, driving wheels on said bogies, a transmission gearing and a lay shaft mounted on the frame of each bogie, a driving gear including coupling rods and connecting rods 20 interposed between each transmission gearing and the driving wheels of a bogie, change speed gears mounted on the frames of said bogies, and a Cardan shaft interposed between each engine and its change speed gear.

25 3. A locomotive comprising in combination, a main frame, two bogies having frames supporting said main frame by means of pivots, two driving engines mounted on the 30 main frame symmetrically with respect to the transverse central plane of the main frame, a transmission mechanism for an engine mounted on each bogie, bogie driving mechanism operated from each transmission mechanism and a flexible driving connection 35 between each engine and its pertaining transmission mechanism.

40 4. A locomotive comprising in combination, a main frame, two bogies supporting said main frame by means of pivots, means pivotally connecting the bogies together, two internal combustion engines mounted on the main frame one over each bogie, a transmission mechanism on each bogie, bogie driving mechanism operated from each transmission 45 mechanism and a universally movable driving connection between each engine and its pertaining transmission mechanism.

45 In testimony whereof, I have signed my 50 name to this specification.

JACOB BUCHLI.
